BY *Wm. Deakins*

ATTORNEY

UNITED STATES PATENT OFFICE.

GUSTAV A. ERIKSON, OF CHICAGO, ILLINOIS.

DESIGN FOR A CHAIR.

57,627.

Specification for Design. Patented Apr. 26, 1921.

Application filed June 9, 1920. Serial No. 387,771. Term of patent 7 years.

To all whom it may concern:

Be it known that I, GUSTAV A. ERIKSON, a citizen of the United States, residing at Chicago, in the county of Cook and State of Illinois, have invented a new, original, and ornamental Design for a Chair, of which the following is a specification, reference being had to the accompanying drawing, forming part thereof.

Figure 1 is a perspective view of a chair embodying my design, and Fig. 2 is a plan view thereof.

I claim:

The ornamental design for a chair as shown.

GUSTAV A. ERIKSON.
